H. A. BEST

FINIAL

Filed July 21, 1927

FIG. 2

FIG. 3

FIG. 4

INVENTOR:
HARRY A. BEST

By Cheever & Cox ATTYS

UNITED STATES PATENT OFFICE.

HARRY A. BEST, OF CHICAGO, ILLINOIS, ASSIGNOR TO H. A. BEST LAMP COMPANY, OF CHICAGO, ILLINOIS, A CORPORATION OF ILLINOIS.

FINIAL.

Application filed July 21, 1927. Serial No. 207,544.

My invention relates to an ornamental finial for a lamp shade and the objects of my invention are to provide a finial constructed and arranged to form a mounting 5 for a transparent or translucent ornamental piece which may be mounted within the body of the finial in a simple manner permitting its ready replacement by a piece of any other desired color; to provide a finial with an 10 internal recess terminating at its upper end with a slot which communicates with the recess and forms opposed bendable jaws which are arranged to permit the passage of the ornamental piece into mounting position 15 on the finial but which can be deformed securely but detachably to hold the piece in display position; to provide these and other objects of invention which will be apparent from a perusal of the following specification 20 when taken in connection with the accompanying drawing wherein,

Figure 1 is a perspective view of a lamp shade with my finial in position,

Figure 2 is a sectional view showing the 25 internal recess for mounting the ornamental glass therein,

Figure 3 is a side view of the finial with the jaws in closed position to hold the glass in place, and

Figure 4 is an end cross-section showing 30 the glass in position but with the jaws open.

Referring now to my invention in detail, my finial is illustrated in its usual position as threaded upon the upper end of the lamp 35 shade rod and clamping the lamp shade in position.

The present construction aims to provide a finial adapted to form a mounting for an ornamental, colorful piece such as a transparent or translucent member, preferably a piece of colored glass which may be inserted 40 within the body of the finial in a manner such that the rough edges of the glass are completely hidden and the glass appears only 45 through registering apertures formed in the side walls of the finial. In this manner a bright attractive appearance is imparted to the lamp shade. Furthermore by my present construction the selected piece of glass 50 may be quickly removed from its mounting in the finial and be replaced by one of another color.

To these ends I provide a finial preferably of cast metal formed with a preferably

round base 2 the interior of which is formed 55 with a threaded bore 4 to receive the upper end of the lamp rod 6. This forms the means by which the finial screws onto the rod to clamp the shade 8 in position as is well known. Preferably the exterior wall of 60 this basal portion is given a suitably ornamental finish. The upper or body portion 10 of the finial is formed relatively thin and broad and is provided with registering apertures through its flat walls providing an 65 opening through which the colored glass 12 may be seen. The interior of the body of the finial is hollow, being formed with an internal recess of desired shape; in the present instance I prefer to form this internal 70 recess square or rather rectangular in outline. It will be noticed that the edges 14 of the registering apertures in the side walls of the body project inwardly from the edges 16 forming the recess and they are preferably 75 arranged in such projecting relation as to form an ornamental opening as indicated in Figure 2 of the drawings. Thus the edges 16 of these inwardly projecting parts completely hide the marginal portions 80 of the glass 12 as it lies within the recess.

The upper portion of the internal recess of the finial communicates with the upper exterior walls of the top of the finial by means of a slot 18 formed in the top thereof, 85 as illustrated clearly in Figure 4 of the drawings. This slot is of a width equal to the width of the internal recess so that the piece of colored glass or other display may be passed through this slot into mounting 90 position. By forming the slot in this manner the opposed upper faces of the finial are formed as opposed, bendable, jaws 20, which since they are relatively thin at this point, and are unreinforced and may be easily 95 swaged or bent together to hold the glass in place in its internal recess. When desirable these jaws may be forced apart and another piece of differently colored glass may be substituted to suit the purchaser. In some instances the edges 14 may be arranged to be 100 pinched together to hold the glass in position in view of the jaws 20 and other means may be availed of for doing this.

It will be apparent that I have provided 105 a most economical and a most simple means for mounting an exchangeable ornamental piece within the finial and in a manner

which permits it to be displayed through the body of the finial and that I have not only so arranged the edges of the aperture through the body of the finial as to form an ornamental outline for the aperture about the transparent piece, but I have also utilized these very ornate edges to hide the raw edges of the piece of glass.

Having thus described my invention what I claim as new and desire to secure by Letters Patent is:—

1. A finial for a lamp shade the body of which is relatively thin and has an opening therethrough, said body at the opening being recessed outwardly beyond the inner edges of the opening to provide an internal seat and the top of the body being slotted and in communication with the internal seat to permit the insertion of an ornamental piece through the slot into the internal seat.

2. A finial for a lamp shade the body of which is relatively thin and has an opening therethrough, said body at the opening being recessed outwardly beyond the inner edges of the opening to provide an internal seat and the top of the body being slotted and in communication with the internal seat to permit the insertion of an ornamental piece through the slot into the internal seat the opposed top portions of the body formed by the slot providing spaced apart bendable jaws adapted to be deformed to hold the ornamental piece within its seat.

3. A finial for a lamp shade having a body formed with a hollowed out interior communicating through the top of the body with the exterior, the body having a display opening therethrough communicating with the hollowed portion of the body so that an ornamental piece when inserted through the opening in the top of the body may be viewed through the display opening.

4. A finial for a lamp shade comprising a body having an internal recess and an ornamental piece inserted in the recess and view- 45

able through an opening in the body.

5. A finial for a lamp shade comprising a body having an internal recess and an ornamental piece inserted in the recess and view- 50

able through an opening in the body, a portion of the walls of the body formed by said recess being deformable to hold the piece within the recess.

6. A finial for a lamp shade comprising a lower round portion having an internally 55 threaded bore, and a relatively flat and thin body portion substantially arrow-shaped, the flat portion having an opening through its upper part and the opening at the margins thereof extending outwardly to provide a 60 substantially rectangular internal seat, with the marginal edges of the opening forming an opening of different design and a portion of the internal seat communicating with the exterior of the body and of sufficient size to 65 permit the insertion of an ornamental piece therethrough into the internal seat and a portion of the walls of the body being readily deformable to hold the piece within its seat.

7. A finial comprising a relatively flat body having an internal recess opening through the edge of the body to permit the insertion therethrough of an ornate piece, the body having an opening through 70 its side and through the recess, the opening being smaller than the internal recess.

8. A finial comprising a relatively flat body having an internal recess opening through the edge of the body to permit the 75 insertion therethrough of an ornate piece, the opening being smaller and of different design than the internal recess whereby the raw edges of the ornate piece are hidden.

In witness whereof, I have hereunto subscribed my name.

HARRY A. BEST.
